CLAIM

The ornamental design for a swivel broom, as shown and described.

DESCRIPTION

FIG. 1 is a perspective view of a swivel broom showing my new design;

FIG. 2 is a front elevational view of the swivel broom of FIG. 1;

FIG. 3 is a rear elevational view of the swivel broom of FIG. 1;

FIG. 4 is a right side elevational view of the swivel broom of FIG. 1;

FIG. 5 is a left side elevational view of the swivel broom of FIG. 1;

FIG. 6 is a top plan view of the swivel broom of FIG. 1;

FIG. 7 is a bottom plan view of the swivel broom of FIG. 1;

FIG. 8 is a perspective view of the swivel broom of FIG. 1, with the handle tilted;

FIG. 9 is a perspective view of a second embodiment of a swivel broom showing my new design;

FIG. 10 is a front elevational view of the swivel broom of FIG. 9;

FIG. 11 is a rear elevational view of the swivel broom of FIG. 9;

FIG. 12 is a right side elevational view of the swivel broom of FIG. 9;

FIG. 13 is a left side elevational view of the swivel broom of FIG. 9;

FIG. 14 is a top plan view of the swivel broom of FIG. 9;

FIG. 15 is a bottom plan view of the swivel broom of FIG. 9; and,

FIG. 16 is a perspective view of the swivel broom of FIG. 9, with the handle tilted.

The features shown in broken lines are environment only and not part of the claimed design.
